CAM WEAR PLATE FOR SWITCH BLADES

Louis C. Carissimi, Fairfield, Conn., assignor to Remington Rand Inc., New York, N. Y., a corporation of Delaware

Application August 4, 1948, Serial No. 42,523

3 Claims. (Cl. 200—166)

1

This invention relates to improvements in electric motors, particularly motors of the make and break contact type used in electric dry shavers.

The invention is directed to improving the make and break contact structure for electro-magnetic impulse motors by providing means for eliminating variations in adjustment between the contacts caused by differences in expansion of the contact arms and the insulating and wear receiving members carried by the contact arms for engaging the contact operating cam. This difference in expansion has resulted in the buckling or warping of the insulating strips on the contact arms laterally toward the operating cam as variations in temperature occur during the operation of the motor causing it to slow down through changing the contact adjustment.

The invention overcomes the disadvantage of prior constructions by providing a transversely slotted or recessed insulating strip formed so that opposite ends of an insulating strip may be riveted to a contact arm with the recessed or slotted portions separating end sections riveted to the contact arm from the central or intermediate portion of the strip. By having the slots extending from one side of the strip to a point adjacent the opposite margin leaving a narrow connecting portion at the opposite margin between the end and intermediate sections and arranging these connecting portions at opposite ends of the intermediate section on opposite sides of the strip, a construction is provided wherein differences of expansion will cause the intermediate section of the strip to move relative to the end sections within the plane of the strip so that the intermediate section of the insulating strip will not warp or bulge away from the contact arm.

In the drawing

Fig. 1 is a plan view of the make and break contact side of an electro-magnetic impulse motor illustrating the invention applied to the contact arms.

Fig. 2 is an enlarged fragmentary cross section taken on line 2—2 of Fig. 1 illustrating the position of the insulating strip constructed according to the invention, on the contact arm and relative to the operating cam.

Fig. 3 shows the insulating and wear receiving strip provided by the invention in perspective on an enlarged scale.

The present invention is designed for use with motors constructed as disclosed in U. S. Patents Nos. 2,368,951, patented February 6, 1945, and 2,415,715, patented February 11, 1947.

The motor has a stator frame 1 carrying a field winding 2. Frame 1 is of substantial U-shape, as illustrated in said patents and in Fig. 1, and has the free ends of the legs forming the U-shape frame providing the stator poles. Frame 1 is preferably constructed of laminated magnetizable

2

metal of a character well-known in the art. The free ends or poles of stator frame 1 have a pair of insulating plate members 3 secured to the opposite side faces thereof in spaced parallel relation by means of suitable bolts 4.

A contact structure of conventional form as shown in the aforementioned patents has a pair of contact arms 5 each carrying a contact point 6 at one end. Each arm 5 has a spring arm extension 7 extending from the other end connected to a supporting bracket 8 suitably secured by rivets or the like to insulating plate member 3. This contact structure is of a conventional type now well-known in the art and is connected in circuit in series with field winding 2.

Insulating and wear receiving strips or members 9 are mounted on contact arms 5, one on each arm, along the inner face for engagement by contact operating cam 10 on the end of the rotor shaft of the motor so that in the rotation of the rotor and rotor shaft the cam will alternately operate to allow the contact points to engage to close the circuit to the field winding 2 and then break engagement of contact points 6 in the conventional manner to provide electro-magnetic impulses for securing rotation of the rotor. The rotor shaft is mounted in suitable bearings in plate members 3 for free rotation. The usual condenser is shunted across the contact points as indicated at 11.

The invention is directed particularly to the construction of insulating and wear receiving strips or members 9. It has been found in the construction and operation of these motors that a great many different types of insulating materials are not well adapted to use as insulating and wear receiving strips 9 due to the fact that they wear too rapidly or have other disadvantages that make them short lived. It has been found that a material known as "nylon" eliminates many disadvantages of other materials when used to provide insulating and wear receiving strips or members 9 in motors of this character. However, this material has a sufficiently different coefficient of expansion from the structure of the contact arms to result in warping of the center portion of each member 9 away from the contact arm and toward contact operating cam 10, when considering the relation of these parts as shown in Fig. 1. Thus warping takes place and increases as the temperature of the motor increases during operation, due to insulating strip 9 expanding to a greater extent than the contact arm. This warping or bulging of the insulating and wear receiving member 9 results from rigidly securing opposite ends of the member to the contact arm by rivets 18 or other similar securing means.

The present invention overcomes this disadvantage caused from the differences in the co-

efficients of expansion of the contact arm and insulating member 9. Accordingly, the invention provides an insulating and wear receiving member 9 having an intermediate section 13 and end sections 14. Members 9 are formed from a single piece of material in providing the sections 13 and 14 through having a strip of material recessed at 15 in transversely extending relation from one side of the strip to the opposite marginal portion. This leaves connecting portions 16 between the intermediate section and each end section. The connecting portion 16 for one end section is at the opposite side of the strip from connecting portion 16 for the opposite end section 14, as clearly shown in the drawing. The end sections of the strip are formed with apertures 17 to receive rivets or the like 18 for securing insulating members 9 to the respective contact arm 5 in the positions shown in the drawing.

When insulating and wear receiving members 9 are mounted on contact arms 5 in accordance with the invention, intermediate sections 13 will be positioned to engage contact operating cam 10. One face of intermediate section 13 and corresponding faces of end sections 14 of each member 9 will engage the adjacent face of contact arm 5 on which it is mounted with end sections 14 rigidly riveted or otherwise secured to contact arm 5.

With this construction it will be understood that as the temperature of the motor increases including an increase in temperature of contact arms 5 and members 9, differences of expansion will occur between members 9 and contact arms 5. With the construction of members 9 as above described and shown in the drawing, the greater expansion of members 9 relative to contact arms 5 will cause the material forming members 9 to twist or warp member 9 within the plane of the member so that intermediate section 13 will twist slightly in edgewise relation with respect to end sections 14 causing connecting portions 16 to bend slightly into curved form while the face of intermediate section 13 and sections 14 and connecting portions 16 adjacent contact arm 5 will remain in engagement with the surface of the contact arm to which it is secured. This will cause the warping of the material of each member 9 to cause movement of portions of the member within its own plane and in a plane at right angles to the warping previously experienced with the use of a solid insulating strip. With this new insulating and wear receiving strip construction intermediate section 13 will not move toward contact operating cam 10 away from the contact arm and therefore will not affect the adjustment of the contact arm and contacts relative to each other and the cam.

It will be understood that the invention provides an insulating and wear receiving member for the make and break contact structure of magnetic impulse motors that will provide for the use of insulating material having different coefficients of expansion from the contact arm without interfering with the adjustment of the contact arms to secure the desired uniform speed of the motor while at the same time providing for the use of insulating material that has better wear resisting properties in engagement with the contact operating cam.

The invention claimed is:

1. In an electric motor wherein a magnetizable core is formed to provide spaced poles, an armature is rotatably mounted in operative relation with respect to said poles, on a shaft rotatably mounted in bearing members supported by said

core, said shaft having a cam member on one end for operating a make and break contact device, and said make and break contact device has a contact arm controlling the make and break of the contact device through oscillation thereof by said cam member, the combination of an insulating strip mounted between said contact arm and said cam member to provide an insulating and wear receiving member for said arm in contact with said cam member, means rigidly attaching opposite ends of said strip to said contact arm, and said insulating and wear receiving member being formed of a strip having slot means between said opposite ends extending transversely across said strip from one side and leaving a bendable marginal portion connecting opposite ends together and bendable in the plane of said strip to compensate for differences of expansion of said contact arm and contact strip to maintain said contact strip in engaged relation with said contact arm throughout the length thereof during relative expansion therebetween.

2. In a make and break contact type of electric motor having a contact arm forming part of the contact mechanism with a central portion opposite an operating cam for oscillating the contact arm, the combination of an insulating and bearing strip between said contact arm and cam with the central portion of one face engageable with said cam and the opposite face bearing against the adjacent side of said contact arm, means rigidly engaging and attaching opposite ends of said insulating strip to said contact arm and said insulating strip having an intermediate and end sections spaced apart in coplanar relation, and bendable connecting portions joining said intermediate section to said end sections at one margin for relative movement of said intermediate section to said end sections during bending of said connecting portions in compensating for differences of expansion between said contact arm and insulating strip.

3. An insulating and wear receiving member for the make and break contact mechanism of magnetic-impulse electric motors, comprising a strip of insulating material formed of an intermediate and end sections arranged in end to end spaced relation, and integral bendable connecting portions attaching each end section to one end of said intermediate section at one side of said section, one connecting portion being at the side opposite the other connecting portion whereby when said end sections are rigidly secured to a contact arm said intermediate section is movable in coplanar relation to said end sections on said contact arm during bending of said connecting portions in compensating for differences of expansion between said contact arm and strip.

LOUIS CONSTANCE CARISSIMI.
